UNITED STATES PATENT OFFICE.

ELMER E. WICKERSHAM, OF STOCKTON, CALIFORNIA, ASSIGNOR TO THE HOLT MANUFACTURING COMPANY, OF STOCKTON, CALIFORNIA, A CORPORATION OF CALIFORNIA.

ROLLER-TRUCK FRAME FOR TRACTION-ENGINES.

1,296,579.

Specification of Letters Patent.

Patented Mar. 4, 1919.

Application filed January 24, 1918. Serial No. 213,469.

To all whom it may concern:

Be it known that I, ELMER E. WICKERSHAM, a citizen of the United States, residing at Stockton, in the county of San Joaquin, 5 and State of California, have invented new and useful Improvements in Roller-Truck Frames for Traction-Engines, of which the following is a specification.

This invention relates to roller truck 10 frames for self-laying track tractors of the type shown, for example, in Patent No. 1,026,037, May 14, 1912, and my copending application, Serial No. 171,172, filed May 26th, 1917.

Frames of this sort have commonly been built up of sheet metal and structural channel iron secured together by riveting. Devices constructed in this manner are very heavy and cumbersome besides being expensive both in material and labor because to prevent them from working loose, particularly at the seam between the vertical and horizontal members, it is necessary to use heavy materials and careful workmanship. 20 In the present invention the object is to overcome these difficulties by devising a construction which will permit an entire frame to be made from one piece and practically at one operation and provided with substantial bracing means to insure the necessary strength and stability.

In accomplishing this result a suitable sheet of metal is formed so that when struck up by a properly shaped die the usual frame 30 having vertical sides united by a horizontal web is formed with flanged forks at one end, the flanges of the forks uniting at the base thereof to form a vertical transverse reinforcing rib for the horizontal web. Bracing means are thus provided to prevent movement of the vertical and horizontal members relatively to one another.

One form which the invention may assume is exemplified in the following description 40 and illustrated in the accompanying drawings, in which—

Figure 1 is a perspective elevational view of a frame embodying the invention.

Fig. 2 is a fragmentary side elevation of 50 the same.

Fig. 3 is a cross section on the line 3—3 of Fig. 2.

Fig. 4 is a cross section on the line 4—4 of Fig. 2.

Fig. 5 is a side elevation of a self-laying

track mechanism, showing the application of the invention thereto.

Fig. 6 is a front elevation of same, the track being removed.

As shown in the drawings, the frame consists of a piece of sheet steel or other suitable material formed with two vertical sides 60 united at their upper edges by horizontal webs 6. The body of the truck frame thus formed is substantially in the shape of an inverted U. The lower edges of the members 5 are turned outwardly to form flanges 7 to which suitable journal boxes 8 for the bearing rollers 9 may be secured. The forward end of the one-piece truck body is cut 70 out and forked, as shown at 10, in Fig. 1, to provide a space in which the track carrying wheel 11 may be journaled between the vertical members 5. The forward ends of the members 5, forming forks 12 having 75 their lower edges tapered off, as shown in Fig. 2, project beyond the horizontal web portion 6, as shown in Fig. 1. These forks 12 straddle and support a sprocket or guide wheel 11 around which the endless track 13 passes. 80 The upper edges of the forks 12 are provided with horizontal flanges 14 on which the bearings of the guide wheel 11 rest. These flanges extend to the base of the forks and curving upwardly continue across, as shown 85 at 15, forming a vertically disposed reinforcing rib and brace extending across the front end of the web 6 and stiffening the whole frame.

The flanges and integral reinforcing rib 90 made in this manner can readily be formed on the truck frame at the same operation in which the whole article is produced, thus permitting of an economical method of manufacture which at the same time produces a 95 frame having a novel construction and including integral reinforcing means.

Various changes in the construction and arrangement of the several parts herein shown and described may be employed without departing from the spirit of my invention as disclosed in the appended claims.

Having thus described my invention, what I claim and desire to secure by Letters Patent is:

1. A one-piece roller truck frame for self-laying track tractors comprising vertical members having flanges at their lower edges forming supports for roller journals, and a horizontal web connecting the upper edges 110

of said vertical members, said web being cut out at one end between the vertical members to receive a track carrying wheel, and provided with a transverse reinforcing rib.

5. 2. A one-piece roller truck frame for self-laying track tractors comprising a horizontal web connecting the upper edges of two vertical members, extensions on said vertical members projecting beyond the horizontal member to form supports for a track carrying wheel, and a reinforcing rib extending across the horizontal member at the base of the extensions.

10. 3. A one-piece roller truck frame for self-laying track tractors comprising a horizontal web connecting the upper edges of two vertical members, extensions on said vertical members projecting beyond the horizontal member to form supports for a track carrying wheel, and a reinforcing rib extending across the horizontal member at the base of

the extensions and curving outwardly to form flanges on said extensions.

15. 4. A one-piece roller truck frame for self-laying track tractors comprising a horizontal web connecting the upper edges of two vertical members, supports for roller truck journals on the lower edges of said members, extensions on said vertical members projecting beyond the horizontal member to 30. form supports for a track carrying wheel, and a reinforcing rib extending across the horizontal member at the base of the extensions and curving outwardly to form flanges on said extensions.

35. In testimony whereof I have hereunto set my hand in the presence of two subscribing witnesses.

ELMER E. WICKERSHAM.

Witnesses:

W. W. HEALEY,
M. E. EWING.
